DETERGENT COMPOSITIONS

Karl Martin Edvin Hellsten, Bromma, Sweden, assignor to Aktiebolaget Henkel-Helios, Stockholm, Sweden, a corporation of Sweden

No Drawing. Filed Oct. 1, 1956, Ser. No. 612,976

Claims priority, application Sweden Oct. 3, 1955

4 Claims. (CL 252—135)

The present invention relates to detergent compositions and more particularly a detergent composition which is better suited for various purposes than prior art detergent compositions.

For many purposes it is desirable that detergent compositions when dissolved in water exhibit a pH value which is at or moderately above the neutral point, e.g. within the range of 7 to 9. This applies e.g. in the case of dish-washing compositions, since at higher pH values fatty substances, lecithins etc. present in the skin are saponified, so that the skin becomes dry. Thus, a composition tending to give a lower pH value is milder to the hands of the user. Another case where a low pH is desirable is the washing of painted surfaces because more strongly alkaline agents may have a degrading effect on substances present in the paint. Another application where a low pH is favorable is the washing of garments made of wool and other proteinaceous fibres, which are washed at a relatively low temperature (usually not above 40° C.), since such fibres are sensitive to a higher alkalinity and furthermore dyes may be attacked at a higher pH. This is also true as regards the dyes in colored garments made from other types of fibres than the abovementioned which are commonly washed at a temperature of about 40–60° C.

On the other hand, in the case of high temperature washing (washing of cotton and linen goods, and the like) it is desirable to have a higher pH value. The cellulosic fibres are less susceptible to attack by alkali, and furthermore the higher pH is advantageous for the detergent action. The dirt consists to a major portion of fatty acids, in which solid particles (soot and dust of various types) are embedded. The washing process consists primarily in a saponification of the fatty acids, whereby the solid dirt is also detached. The saponification occurs most readily at a pH of 9.5 or above but since the cellulosic fibres are not entirely insensitive to alkali a pH of about 11 is usually not surpassed.

The main object of the present invention is to provide a detergent composition which in aqueous solution at a lower temperature, e.g. up to about 50 or 60° C., maintains a pH within the range of about 7.5 to 9.5, preferably about 8.5, during at least a substantial period of time, but after some time of residence at a higher temperature (e.g. about 80 to 100° C.) obtains a pH within the range of about 9.5 to 11 preferably 10 to 10.5. This object is realized by incorporating magnesium oxide in the composition.

The invention is broadly applicable to detergent compositions comprising as the active detergents ingredient a synthetic detergent of anionic or nonionic type. Examples of anionic detergents which may be used in compositions embodying this invention, include alkyl aryl sulfonates, in particular alkylbenzene sulfonates in which the alkyl group contains from 8 to 20 carbon atoms, e.g. dodecylbenzene sulfonate, octadecylbenzene sulfonate; higher aliphatic sulfates and sulfonates, in which the aliphatic radical comprises from 8 to 20 carbon atoms, such as lauryl sulfate or lauryl sulfonate; and higher fatty acid amides, in which the acyl group contains from 8 to 20 carbon atoms, such as tallow fatty acid amide, cocoa fatty acid amide and the like. The sulfonates and sulfates referred to above are commonly

2

used in the form of alkali metal sulfonates, in particular sodium sulfonates, although the corresponding salts of ammonium or organic bases, such as, e.g. ethanol amine, triethanol amine and the like, may also be used. Examples of nonionic detergents which may be included in compositions according to this invention, include poly-glycol ethers of higher aliphatic alcohols and polyglycol ethers of higher fatty acids, in which the alcohol group and the fatty acid group respectively comprises from 8 to 20 carbon atoms and which contain 10 to 50 ethylene oxide ($—CH_2CH_2O—$) units per molecule. A great number of anionic and nonionic synthetic detergents of the above and other types and processes of preparing them are well-known in the art and described in the technical and patent literature. It will be understood that insofar as the present invention is concerned the type of detergent is not essential, since the pH increase contemplated by this invention is not dependent on the detergent used. It is to be noted that soaps are not suitable since they tend to impart a too high pH value per se. The amount of nonionic or anionic synthetic detergent will usually be about 15 to 50% by weight of the detergent composition, preferably about 15 to 25% (on a dry basis).

In addition to the synthetic nonionic or anionic detergent, the detergent compositions contemplated by this invention comprise an alkali metal phosphate which acts as a builder. As phosphates which may be used there may be mentioned sodium or potassium salts of ortho, meta, poly and pyro-phosphoric acids, e.g. sodium hexametaphosphate, sodium pyrophosphate, sodium tri-polyphosphate ($Na_5P_3O_{10}$), disodium orthophosphate etc. The amount of phosphate will usually be about 25 to 50% by weight of the detergent composition (on a dry basis).

In accordance with the present invention it has been found that a detergent composition of the type above referred to containing a nonionic or anionic synthetic detergent and a phosphate and formulated so that its pH when dissolved in water is within the range of 7.5 to 9.5 may be imparted the characteristic of rapidly obtaining a pH of 9.5 to 11 when the solution is heated (e.g. to 80 to 100° C.), while no or at least only a slow increase in pH occurs at room temperature or slightly elevated temperature (e.g. up to 60° C.), by incorporating magnesium oxide in the composition. When the solution is heated, the magnesium oxide reacts with the alkali metal phosphate to form alkali and magnesium phosphate which is less dissociated than the alkali metal phosphate, whereby pH will increase. Since this reaction occurs only slowly at a lower temperature, there will be only a slow increase in pH at room temperature. The amount of magnesium oxide may be about 1 to 10% by weight of the detergent composition (on a dry basis).

It has also been found, in accordance with two preferred embodiments of the invention, that the desired effect may be improved with respect to the constancy of the pH value at a lower temperature in two different ways.

In one preferred embodiment, an alkali metal bicarbonate is incorporated in addition to the magnesium oxide; surprisingly, the alkali metal bicarbonate minimizes the increase in pH at a lower temperature but does not prevent the desired pH increase at a higher temperature. The amount of bicarbonate may be about 5 to 20 times the amount of magnesium oxide or 5 to 40% by weight of the detergent composition (on a dry basis).

In the other preferred embodiment, the magnesium oxide is added in the form of a powder the individual particles of which are coated with a substance which melts and is dispersed or dissolved in the washing solution at about 50 to 60° C., whereby the magnesium oxide

remains inactive or "masked" at a lower temperature, but upon increase in temperature above the melting point of the coating substance, will be released and will provide the desired pH increase. As this coating substance it is per se possible to use any substance with a suitable melting point, e.g. paraffin. It is preferable, however, to employ a substance which is advantageous for the detergent action, since such an inert substance as paraffin is actually a load for the detergent composition. For this reason it is preferred to use as the coating substance higher fatty alcohols having a melting point within the range referred to e.g. cetyl alcohol or stearyl alcohol, which upon melting and dissolution in the detergent solution exhibit a certain dirt dispersing action. Other substances having a similar effect are ethylene oxide addition products of the above-mentioned fatty alcohols comprising only a few, e.g. 1 to 4 ethylene oxide units per molecule of fatty alcohol. The coated magnesium oxide powder is suitably prepared by blending magnesium oxide powder with the molten coating substance, e.g. cetyl alcohol, and spraying the mixture into cold air so that the molten coating substance solidifies and forms a film around each magnesium oxide particle. The proportions of the two substances may be such that the coated powder contains 25 to 75% of MgO and 75 to 25% of the coating material, by weight. Preferably, the composition is 40 to 60% of MgO and 60 to 40% of the coating substance, by weight. The magnesium oxide may be used in such a coated form even when bicarbonate is present, although the importance of the coating is less in this case.

To obtain the lower pH value desired at the lower temperature, it may in many cases be desirable to admix acidic substances. To this end it is known to use as the phosphate sodium acid pyrophosphate ($\text{Na}_2\text{H}_2\text{P}_2\text{O}_7$), which may also be used in compositions according to this invention. Since, however, this salt has a relatively strong buffering action, which may counteract the desired pH increase at the higher temperature, so that this does not become as marked as desirable in many cases, it may in certain cases be more advantageous to employ a small amount of a strong acid, such as sulfuric acid, to obtain a low pH. The amount of acid may be up to 10% by weight of the finished mixture (on a dry basis).

In addition to the above mentioned ingredients the detergent compositions of this invention may contain any other desired ingredients which are common in detergent compositions of the type here contemplated. Thus, the composition usually comprises a high-molecular weight substance, such as a cellulose ether, in particular the sodium salt of carboxymethyl cellulose, or polyvinyl-pyrrolidone, e.g. in an amount of 0.5 to 2% by weight of the mixture (on a dry basis). Other additives which are frequently present are silicates, such as water glass (e.g. 2 to 7%), other alkali metal salts, such as sodium sulfate (e.g. 5 to 20%), a perborate (e.g. 5 to 20%) or other bleaching agents, stabilizers for the perborate, e.g. ethylenediamine tetraacetic acid, and fluorescent dyes (so-called optical brighteners; e.g. 0.01-0.1%). Other additives are of course possible without departing from the spirit and scope of the invention. It will be noted, however, that greater amounts of substances which tend to give high pH values already at a low temperature will not be included, as also substances which would tend to interfere with the reaction desired at the higher temperature.

The compositions of this invention are preferably prepared in the form of a powder, although they may also be prepared in the form of liquids. When used for washing purposes, an amount of about 1 to 10 g. of the compositions (on a dry basis) will be dissolved in 1 liter of water.

The invention is illustrated, but not restricted by the following examples.

Example 1

40 kg. of 98% sulfuric acid are added to 400 liters of

water while cooling. To the solution there are added, with agitation, 400 kg. of sodium tripolyphosphate ($\text{Na}_3\text{P}_3\text{O}_{10}$), the temperature being kept below 70° C. Thereupon, 350 kg. of sodium sulfate are added to the solution followed by 850 kg. of an aqueous paste comprising 33% of a detergent mixture consisting of 5 parts of sodium dodecylbenzene sulfonate and 2 parts of sodium cetyl alcohol sulfate, to which paste there have previously been added 20 kg. of a technical sodium carboxymethylcellulose (67% of NaCMC, the remainder being by-product salts and water), 14 kg. of a 40% aqueous solution of ethylene diamine tetraacetic acid and 0.76 g. of 4,4' - bis-(2,2-diaminotriazinylamino)stilbene-2,2'-disulfonic acid as an optical brightener. The resulting slurry is spray-dried to form a powder.

250 kg. of the powder are mixed with 67 kg. of sodium perborate and 36 kg. of a "masked" magnesium oxide powder comprising 55% of magnesium oxide and 45% cetyl alcohol. This masked magnesium oxide powder is obtained by stirring magnesium oxide powder into molten cetyl alcohol and spraying the mixture into cold air.

12 kg. of washing were added to a washing machine together with 50 liters of water and 210 g. of the powder prepared as above described. The pH of the mixture at 25° C. was 8.2. The contents of the machine were heated to 85° C. in 30 minutes whereupon the pH had increased to 9.2. After 15 minutes at 85° C. pH was 9.8.

In another washing test at 40° C. the pH was substantially unchanged.

Example 2

7.05 g. of the powder obtained as described in the first paragraph of Example 1 were mixed with 0.95 g. of sodium perborate and 0.72 g. of a "masked" magnesium oxide (containing 40% of MgO and 60% of cetyl alcohol). The mixture was dissolved in 2 liters of water and the solution was boiled in a pot together with 200 g. of washing which was heavily soiled with fatty acids. The solution pH was initially 8.2, after heating to 100° C. (10 minutes) 9.2 and after 15 minutes at 100° C. 9.4.

In another similar test, the same mixture was used except that the magnesium oxide was omitted. In this case, the initial pH was 8.2, after heating to 100° C. (10 minutes) it was 8.1 and after 15 minutes at 100° C. it was 8.1.

In the examples below, the composition of a number of additional detergent mixtures in accordance with this invention is given in percent by weight. These compositions may be prepared in substantially the same manner as the composition of Example 1, by making an aqueous slurry of all ingredients except perborate and magnesium oxide and bicarbonate (if any), spray-drying this slurry to form a powder and blending the powder with perborate, magnesium oxide and any bicarbonate. The "optical brightener" mentioned in the examples below is the same as that of Example 1. The term "E:O" and the number indicated together with this term in Examples 4, 5 and 7 shows the number of ethylene oxide ($-\text{CH}_2\text{CH}_2\text{O}-$) units present per molecule of the compound in question. The pH values given are determined in solutions containing 4 g. per liter of the compositions.

Example 3

	Percent
65 Sodium dodecylbenzenesulfonate	20
Sodium tripolyphosphate	20
Sodium acid pyrophosphate	10
Sodium carboxymethylcellulose	1
70 Sodium silicate (water glass, $\text{Na}_2\text{O} \cdot 3.3\text{SiO}_2$)	4
Magnesium oxide	5
Sodium perborate	12
Sodium sulfate	20
Optical brightener	0.06
Water	Remainder

5

This composition when dissolved in water of room temperature has a pH of 8.7. After half an hour at 25° C., the pH is 8.9, after an hour at 50° C. 9.5, and after half an hour at 100° C. 10.0.

Example 4

	Percent
Sodium dodecylbenzenesulfonate	15
Nonylphenol polyglycol ether (20EtO)	5
Sodium tripolyphosphate	30
Sodium bicarbonate	25
Sodium carboxymethylcellulose	1
Sodium silicate (water glass)	4
Sodium perborate	12
"Masked" magnesium oxide (50% MgO, 50% cetyl alcohol)	15
Sodium sulfate	2.5
Optical brightener	0.06
Water	Remainder

When dissolved in water of room temperature and up to 60° C., this composition gives a pH of about 9.0. After half an hour of boiling of the solution, its pH increases to 10.0.

Example 5

	Percent
Stearyl alcohol polyglycol ether (30EtO)	15
Sodium tripolyphosphate	35
Sodium bicarbonate	25
Magnesium oxide	2
Sodium carboxymethylcellulose	1
Sodium silicate (water glass)	6
Sodium perborate	8
Sodium sulfate	5
Optical brightener	0.05
Water	Remainder

This composition, when dissolved in water of 25° C. has a pH of 9.3. After heating to 100° C. the pH increases to 10.3.

Example 6

	Percent
Sodium dodecylbenzenesulfonate	18
Cocoa fatty acid amide	4
Sodium tripolyphosphate	32
"Masked" magnesium oxide (50% MgO, 50% stearyl alcohol)	45
Water glass	5
Sodium carboxymethylcellulose	0.5
Sodium perborate	14
Sulfuric acid	4.50
Sodium sulfate	12
Optical brightener	0.06
Water	Remainder

When dissolved in water of 25° C., this composition had pH 8.5, after heating to 100° C. pH 10.0.

Example 7

	Percent
Tall oil acid polyglycol ester (25EtO)	17
Sodium tripolyphosphate	20
Sodium hexametaphosphate	10
Sodium bicarbonate	20
"Masked" magnesium oxide (60% MgO, 40% cetyl alcohol)	3.5
Polyvinylpyrrolidone	0.5
Sodium perborate	10

	Percent
Sodium sulfate	15
Water	Remainder

When dissolved in water of 25° C. this composition shows pH 9.4, after heating to 100° C. pH 10.5.

What is claimed is:

1. A detergent composition comprising 25 to 50% of at least one alkali metal phosphate selected from the group consisting of sodium and potassium salts of orthophosphoric acid, metaphosphoric acid, polyphosphoric acid and pyrophosphoric acid, 1 to 10% of magnesium oxide, and 15 to 50% of a detergent selected from the group consisting of a nonionic non-soap synthetic organic detergent and an anionic non-soap synthetic organic detergent, said composition having a pH within the range of 7.5 to 9.5 when admixed with water at a temperature below approximately 60° C., said magnesium oxide being present in an amount providing a pH within the range of 9.5 to 11 when said composition is admixed with water at a temperature between approximately 80 and 100° C., said magnesium oxide being present in the form of a powder the particles of which are coated with an organic coating substance which is solid and insoluble in water at a temperature below approximately 60° C. to prevent said magnesium oxide from dissolving in said solution at a temperature below the last mentioned temperature, said organic coating substance melting at a temperature of 50 to 60° C. to provide for dissolving of said magnesium oxide in water at a temperature above approximately 60° C., said organic coating substance being present on the particles of magnesium oxide in an amount between 25 and 75% by weight of the coated magnesium oxide.

2. A detergent composition as in claim 1 which also comprises an alkali metal bicarbonate.

3. A detergent composition as in claim 1 in which said magnesium oxide particles are coated with a fatty alcohol melting at 50 to 60° C.

4. A detergent composition as in claim 3 in which said fatty alcohol is cetyl alcohol.
